SIGNAL LIGHT

William Lintern, Cleveland, and William A. Lintern, Brook Park Village, Ohio, assignors to The Lintern Corporation, Cleveland, Ohio, a corporation of Ohio

Application December 31, 1938, Serial No. 248,786

6 Claims. (Cl. 240—106)

This invention relates to an improvement in signal lights of the type used for example to indicate emergency exits, fire extinguishing equipment, danger points of indoor and outdoor traffic routes etc. and for conveying definite messages of any desired nature.

Such signal lights should be so constructed that light displayed by them will be clearly visible from as many directions as required by their specific uses. One of the objects of the present invention is to amplify the visibility range of signal lights, particularly in planes along which the signal is most likely to be viewed, but without critically reducing the visibility range when viewed along other planes.

Another object is to provide an improved prismatic lens of the generally cylindrical type adapted to enclose and protect a light source and which is arranged to expose magnified images of said source sharply and clearly to view all around the light source, particularly at angles nearly normal to the lens axis and radiating from the center of such source, but with sufficient clearness for practical signaling purposes at all other angles about such center and passing through exposed wall portions of the lens.

Another object is to provide an improved means for conveying self-explanatory messages or legends in conjunction with amplification of visibility range of a light source as outlined above.

Specific objects include the provisions of an improved arrangement of prism faces on a signal lens, and a more effective combination of light and lens characteristics.

Other objects and features of the invention will become apparent from the following specification relating to the accompanying drawings, in which

Fig. 1 is a view showing features of the invention embodied in a lens, light source and legend display means on a part of the lens, one form of mounting for the various parts and a visibility (light curve) diagram also being shown on the view; Fig. 2 is a full longitudinal sectional view of the lens, showing at one side the manner in which light rays are projected from the lens at various angles and at the other side the angular relationship of reflecting and refracting prisms of the lens wall; Fig. 3 is a partial sectional view showing a modified means for displaying a legend on the lens; and Fig. 4 is a side elevation of the lens showing the manner in which the light source is displayed at one angle of view.

Referring to Fig. 1 a suitable mounting 1 for the lens 2 and light bulb 3 may comprise a metal

casting or stamping which is hollow and has outlet openings 5 and 6, variously arranged to receive supporting or conductor-carrying pipes, one such being shown at 7 entering the upper opening which may be threaded to receive the pipe. The mounting may be greatly modified. As shown the mounting has a flange 8 at its lower rim, against which a flange 9 of the lens may be removably secured, a gasket 10 being interposed which is operable as a seal and to reduce likelihood of fracturing of the lens when the same is made from glass, as preferred. A lens-attaching ring 12 encloses the flange 9 of the lens and the ring and flange 8 can be secured by bolts 13 which pass through notches or holes in the flange of the lens.

The lens, which is of generally cylindrical form and closed at the end opposite the mounting, can be disposed in any conceivable position, but for illustration and purposes of description, it will be assumed that the lens has its central axis positioned vertically. The lamp (light source) is maintained by its socket and the attachment of the latter (not shown) to the mounting 1 in such position that the effective center of the filament or incandescent element is approximately at the position indicated by the circle L on Fig. 1. The lamp can occupy other positions (moved up or down) depending on the expected average angle of view with respect to the longitudinal axis of the lens. However, in the normal positioning of the lamp filament or incandescent element such as V in Fig. 2, (representing a low wattage vapor lamp) the center of radiation of light is opposite an annular prism portion 15 of the lens located at a portion of the lens which, exclusive of the prisms, is substantially cylindrical. Above the prism 15 is a prism 16 having a major face somewhat broader than that of the prism 15. The angular relationships of the prism faces are shown at the right of Fig. 2 and these angles and their functions will be referred to later herein.

Above prism 16 are two or more narrower prisms 17 and 18 and, above these, the lens can be smooth and nearly cylindrical, as at 19 both inside and outside for the purpose of effectively displaying a legend, as will later be described; or there can be a plurality of prisms on the order of 17 and 18 if no legend is to be displayed. Below the prism 15 the lens, (exclusive of prisms thereon) becomes spherically convex and the annular prisms on the convex or globular portion of the lens are indicated at 20, 21, 22, 23, 24, 25, 26 and 27, respectively. The faces on one side of the apices of the prisms (generally above the

apex in each case) are indicated as at 16a, 17a, etc. and those faces below the apices are indicated as at 16b, 17b, etc.

The angularity of the prism faces is fully described on Fig. 2 at the right and, for convenience, these angles are related to horizontal planes, i. e. normal to the axis of the lens. The angles may vary a few degrees, say within a total of five degrees and the number of prisms may, of course, be greater or less than as shown.

Specific attention is called to the angularities of prisms 15 to 18 and 20 to 23 which are the most important from a practical standpoint because these are the prisms which are desired to become effective to display images of the light source at longest range and through a fairly wide vertical angle. Display of such images is less important generally endwise of the lens because with the axis of the lens extending vertically (as usual) it is practically never very far to the limit of the distance from which the signal can or need be observed.

The prism face 15a is at a slight angle to the opposite inside face of the lens (about 4° as shown) and the broad area of this portion exposes the image of the filament or incandescent element through a considerable vertical angle. Similarly the prisms 16 and 20 and to a diminishing extent the other prisms between 18 and 23, by reason of the angularity of the relatively broad faces of the prisms shown, expose images of the filament through wide vertical angles such that persons viewing the signal light from well above and well below the horizontal plane of the light source, see the filament image either on a major or minor face of each of the prisms mentioned.

Summarizing the above described arrangement of the more important outer prism surfaces in terms of convergence upwardly or downwardly, it will be seen that complements of the angles shown at the right on Fig. 2 give the following: The relatively broad surface 15a converges upwardly at 8°; the surface 16a at 44°, and the surfaces 17a and 18a at 90° and 104°, respectively. Also the surface 20b converges downwardly at 48°; the surface 21b at 92°; 22b at 120°, and 23b at 150°. It can also be observed from Fig. 2 that the faces 16a, 17a and 18a successively increase in convergence upwardly and successively decrease in width upwardly, and that the surfaces 20b, 21b, 22b and 23b, part of which lie on the globular portion of the lens, successively increase in convergence downwardly and, generally speaking, increase in breadth downwardly. This successive increase in angle of convergence upwardly and downwardly as to the respective prism surfaces just mentioned and the relationship of breadth of the respective prism surfaces has been found to amplify the light source as observed from points generally at right angles to the lens axis and in the approximate elevation of the central prism 15 about as illustrated in Fig. 4.

The result is that throughout the critical vertical angle range for practical signalling purposes, observers see the filament image multiplied or amplified on the lens as a broad, nearly continuous, band of light. The light direction lines at the left on Fig. 2 indicate the vertical amplitude of the various prisms in transmitting the incandescent element images. The relationship of the image transmission properties of the various prisms to each other requires no specific description in view of the diagram.

When using a 100 watt clear bulb having a conventional filament, the light strength of the signal throughout a range of 120° is as shown by the light curve C on Fig. 1, wherein the extent of any one portion of the curve from the center of radiation of light indicates—in candle power—the signalling strength of the light at the angle of view of that portion about the center of radiation of light. For illustration, viewing 10 of the light at 90° from the vertical axis affords a candle power of 469 as indicated and the candle power at close range and at 10° intervals is as marked (140 at 80°; 75 at 70° etc.).

Now, by using a low wattage vapor lamp with 15 a disc-like incandescent element (V in Fig. 2) which is preferably illuminated on both sides of the disc, top and bottom in the position shown, solid, generally elliptical images appear on the major faces of the prisms, with the result that 20 a much stronger signal effect is obtained than with the ordinary glass globe or lens and much higher wattage bulbs with conventional filaments. Fig. 4 illustrates the above, the light spots on the black field being the reflected images 25 as they appear at about six feet from the lens (point of view at level of prism 18).

Referring further to Fig. 2 and particularly the lines at the left of the view, it is apparent that the image of the incandescent element will 30 remain visible on the face 15a of the prism 15 through the angle included by the lines a and b indicating resultants of refraction of the lens; that the image on face 16a of prism 16 will be 35 visible through the angle represented by lines c and d; on 17a by the angle represented at e and f and on 18a by the angle represented at g and h. The relative angles of the prism faces and inner lens wall are such that at various elevations of 40 the point of view above and below the horizontal plane of the light source one is certain to be within several of the included angles described, from b to g, if at any appreciable distance from the signal light and will see the incandescent element image sharply defined in several places 45 on the lens.

At higher elevations, one sees the image on faces 15a, 20a, 20b and 21a, 21b, etc., as will be clear from the diagram without specific description. The lowest elevation served by the lower prisms down to 23 is indicated by the line i, but at such elevations one would also see the image of the incandescent element on faces 15a, 16a and possibly others. The image displaying angles 55 of the lowermost prisms are also indicated on Fig. 2 by relatively radiating lines (not indicated by any characters). The light curve on Fig. 1 is indicative of the candle power value at different angles of view generally endwise of the lens.

The preferred manner of displaying legends is by means of a detachable mask 35, the cylindrical portion 19 of the lens and a conical or globular reflector 36 inside the lens. The mask is cut out as at 38 in the manner of a stencil so that rays from the light source are projected by the reflector through the letters or symbols of the legend in generally diverging arrangement as indicated conventionally at the left of Fig. 2. The mask can comprise an extension of the attaching ring 12 previously described, or detachably mounted on the signal light in any other appropriate fashion so that one legend can readily be substituted for another at any time. The reflector should have a stippled or crinkled surface to diffuse the light generally and distribute

light reflections uniformly against the legend. The reflector may be secured in place by means of a flange 39 overlying the flange 9 of the lens and clamped in place as shown in Fig. 1.

Another way of displaying a legend is shown by Fig. 3 wherein indented portions 40 of the lens wall portion 19 delineate the legend or symbol areas which are transparent or translucent. Surrounding these areas, as between parallel concentric ribs 42, the lens can be rendered substantially opaque as by black vitreous enamel 43 applied during formation of the lens generally. The same or a similar arrangement of symbols and opaque background can be made integral with the lens but on the outside of it if desired.

We claim:

1. A signal light having a lens comprising a hollow translucent body of generally cylindrical form and substantially closed at its lower end by a globular lens portion, and adapted to enclose an incandescent element so that its center of emanation of light is located in a plane near the lower limit of the cylindrical portion, prisms on the cylindrical wall including an annular wall portion opposite said element center, the outer surface of which wall portion converges upwardly at a relatively narrow angle, annular outer surfaces nearly normal to the lens axis adjacent said wall portion above and below it, a broad outer prism surface adjacent to the upper abrupt surface and converging upwardly at approximately 44°, a less broad outer prism surface adjacent the lower abrupt surface and which converges downwardly at approximately 48°, narrower annular prisms above the upper broad surface and with outer face surfaces which converge at increasing angles upwardly, and annular prisms below the said downwardly converging surface, outer faces of which latter prisms converge downwardly at increasing angles.

2. The arrangement of lens according to claim 1 wherein the outer surface of the annular wall portion opposite said element center converges upwardly at approximately 8°.

3. The arrangement of lens according to claim 1 wherein the prism surfaces below the surface

which converges at approximately 48°, converge, in succession, downwardly at approximately 92°, 120° and 150°.

4. The arrangement of lens according to claim 1 wherein the prism surfaces above the surface which converges upwardly at approximately 44°, converge, in succession, at approximately 90° and 104°.

5. A signal light having a lens comprising a hollow translucent body of generally cylindrical form and substantially closed at its lower end by a globular lens portion merging with the cylindrical portion, and adapted to enclose an incandescent element so that the center of emanation thereof is located in a plane near the lower limit of the cylindrical portion, annular prisms on the cylindrical wall portion including a prism with a slightly upwardly converging relatively broad annular outer surface located approximately in the plane of said center, other annular prisms thereabove and therebelow on the cylindrical portion, separated from the first described prism and from each other by abrupt relatively narrow surfaces which converge toward points near said center of emanation, said other prisms which lie above the first described prism having outer relatively broad faces but of successively decreasing width upwardly and successively increasing angle of convergence upwardly, and those lying below the first described prism being carried partly on the globular portion and having outer relatively broad surfaces which are generally of successively increasing width downwardly and of successively increasing convergence downwardly.

6. A signal light according to claim 5 wherein there is an additional series of annular prisms on the globular portion with downwardly slightly converging outer faces which successively decrease in convergence downwardly, separated by upwardly widely converging outer surfaces, the width of each of which is about the same as the face of the slightly downwardly convergent face to which adjacent.
